INVENTOR

BY *Victor J. Evans*

ATTORNEY

WITNESS: *R. G. Wise*

UNITED STATES PATENT OFFICE.

LAUREN B. MERRIAM, OF TALLAHASSEE, FLORIDA.

NUTCRACKER.

Application filed April 8, 1922. Serial No. 550,717.

To all whom it may concern:

Be it known that I, LAUREN B. MERRIAM, a citizen of the United States, residing at Tallahassee, in the county of Leon and State 5 of Florida, have invented new and useful Improvements in Nutcrackers, of which the following is a specification.

My present invention has reference to a nut cracking machine.

10 My object is to produce a device of this character by the use of which nuts can be cracked in an easy, accurate and expeditious manner.

15 A further object is to produce a nut cracking device in which a toggle lever system is employed for moving a movable jaw toward a stationary jaw in a firm and positive manner to effectively crack nuts between the jaws.

20 A further object is to produce a nut cracking device in which a support is integrally formed with a jaw, a second jaw cooperating with the first mentioned jaw, a lever being pivotally connected to the support and a

25 link connection being provided between the lever and the movable jaw whereby the swinging of the lever will forcibly move the last mentioned jaw toward the first mentioned jaw to crack a nut between the jaws,

30 and also whereby the last mentioned jaw will be quickly brought away from the first mentioned jaw to release the cracked nut from between the jaws.

35 A still further object is to produce a nut cracking device that includes a fixed jaw and a movable jaw which is adjustable with respect to the fixed jaw, and means for moving the last mentioned jaw toward or away from the first mentioned jaw.

40 The foregoing, and other objects which will present themselves as the nature of the invention is better understood, may be accomplished by a construction, combination and operative association of parts, such as is disclosed by the drawings which accompany 45 and which form part of this specification.

In the drawings:—

Figure 1 is a side elevation of the invention.

50 Figure 2 is a top plan view thereof.

Figure 3 is a fragmentary view of a construction substantially similar to Figure 1 but illustrating the movable jaw thereof in the nature of an adjustable member.

55 Referring now to the drawings in detail,

the body member or casting 19 is provided with a downwardly extending portion 20 terminating in an outwardly directed flange 21, the said flange having a threaded opening therethrough through which is screwed 60 a bolt 22. The bolt has its outer end provided with an enlargement in the nature of a hand grip and its opposite end has swiveled thereon a head 23. The body 19 may thus readily be secured upon a support. 65 The end of the body 19 above the flange 21 is integrally formed with an upstanding jaw 24, the inner or active face of the said jaw having a concavity for the reception of a nut. The body 19, at its forward end is 70 disposed at an upward angle, the front end thereof being bifurcated and received in the bifurcation there is a handle 25 pivoted to the support, as at 26.

Straddling the body and the depending 75 portion 20 thereof, there are the arms 27 on the lower end of the movable jaw 28. The arms 27 are pivoted to the portion 20 of the body, as at 29. The active face of the jaw 28 is concaved, the concavity being disposed 80 opposite the concaved active face of the jaw 24. The jaw 28 has its opposite face provided with an outstanding ear 30 to which is pivoted a link 31, the said link being also pivoted to the end of the handle 25. The 85 operation of this device will, it is thought, be perfectly apparent.

In Figure 3 of the drawings, the construction is similar to that referred to in connection with Figures 1 and 2, the only 90 difference being that the swinging member 28 has adjustably arranged thereon a supplemental jaw 32.

It is thought that the foregoing description, when taken in connection with the 95 drawings will render the construction and operation of the improvement obvious to those skilled in the art to which such inventions relate, but it is thought necessary to add that I do not wish to confine myself 100 to the details of construction herein set forth and that I am entitled to all such changes therefrom as fall within the scope of what I claim.

Having described the invention, I claim:— 105

A device of the character described comprising a body, a portion depending therefrom, arms designed to straddle said body and being pivotally secured adjacent the lower end of the depending portion, said 110

body having one end disposed at an upward inclination and being terminally bifurcated, a jaw rising from the opposite end of said body and in advance of the depending portion, a second jaw carried by the pivoted arms and being adapted to swing with the arms toward and away from the first mentioned jaw, a link pivotally secured

to the second mentioned jaw, a handle fulcrumed in the bifurcations of the upward inclined end and being pivoted at its end to the links, and means for securing the body to a support.

In testimony whereof I affix my signature.

LAUREN B. MERRIAM.
